UNITED STATES PATENT OFFICE

1,924,473

GOLF TEE

William C. Walsh, Omaha, Nebr.

Application September 16, 1930
Serial No. 482,236

1 Claim. (Cl. 273—33)

My present invention relates to the art of golfing equipment, and more specifically to a golf tee.

In the past it has been customary to use damp sand upon which to peak a ball so that in driving it would be possible to strike well down on the golf ball so as to give it loft even with a comparatively straight-sided club, such as a driver. This method was found inconvenient and various devices have been produced to eliminate the same. Among these the most common is a little pin having an enlarged head, which is counter sunk to provide a seat for the ball. These are made of wood, paper or metal. These devices are rather expensive when it is considered that they are rarely recovered after being hit with a driver, in addition to which they are quite often broken with the stroke. This condition led to the production of tee devices, most common among which is a rubber strip which terminates in a raised cup-like portion and which because of its size cannot be easily lost. This has the disadvantage of presenting considerable mass, which seriously interferes with the smooth follow-through which most golfers endeavor to effect.

In my present invention I have produced a device which I believe overcomes the objections to the devices enumerated above, therefore:

The principal object of my invention is to provide a golf tee which is arranged to be securely anchored when in use so as to prevent loss of the same.

A further object is to provide a golf tee which is so constructed that the member which actually supports the golf ball has very little mass and will not interfere in any way with the completion of the golf stroke.

A further object is to provide a golf tee which is so constructed that it is practically indestructible.

A final object is to provide a golf tee which admits of very economical manufacture so that its retail selling price may be kept quite low.

Other and more specific objects will be apparent from the following description taken in connection with the accompanying drawing, wherein:

Figure 1 is a top plan view showing my device as it is used with a dotted line position showing the position assumed by the ball support at the completion of a drive.

Figure 2 is an elevation of my device showing the same with a golf ball held in the most favorable position for driving the same.

Figure 3 is a vertical sectional view to better

show the method of attaching the bearing washer and support.

Referring to the drawing throughout which like reference characters indicate like parts, numeral 10 designates the pin portion of my device. This I normally prefer to form with a chisel like point 12. This prevents the pin turning and in this way there is little tendency to loosen the pin in its contact with the ground. This feature I have found of considerable value as a number of similar devices have been observed in use wherein the pin 10 was formed as a continuation of the ball holding member and was thus caused to revolve each time the ball was struck. This proved to be very unsatisfactory, particularly at driving courses where it is desired to drive a large number of balls from a single point.

Secured to pin 10 is a bearing washer 14. I believe it will be apparent that this washer might be formed as part of pin 10, but I have found it may be more economically produced by using a separate washer 14, and securing it at a point as illustrated in Figure 3, by any of the various means known in this line of work. I have illustrated a shoulder 16 formed in the pin 10. A cut washer 14 is then pressed upon pin 10 and comes to rest against this shoulder. Beneath washer 14 I force up the metal in two or more places to form the bosses 18. These I have found will retain the washer 14 rigidly in place.

As a convenience in manufacture I form the upper end of pin 10 with a body portion 20 and a head 22. The body portion 20 forms a bearing or journal for the end of the ball support member 23. To save manufacturing costs I have provided that the end of member 23 be wound helically about journal 20, as will be most clearly observed in Figure 3. This I have found may either be wound in place upon journal 20 after the head 22 is formed, or it may be wound separately and slipped upon pin 10, over the small shoulder 16, before the washer 14 is secured in place. Many alternative schemes no doubt will suggest themselves; for instance, the head 22 might be in the form of a screw which would be tapped into the upper end of pin 10. This would be a very satisfactory construction, but would be more expensive and would have the disadvantage of possibly working loose through use.

The opposite end of member 23 is formed as a loop which can be best observed in Figure 1. This provides a circular support into which the ball can be securely seated. I have found it most satisfactory to face the bend as illustrated in Figure 1. In this way there is no danger of the

golf club tending to distort the loop 24 by catching the extreme end.

Method of use

- 5 In using my device, the pin 10 may be put in place when driving off the tee at any desired spot within the limits provided. When used on fairways, however, as is quite common in certain golf courses, during those periods when the course 10 is soft from rain or frost, the loop 24 is placed over the center of the ball and the pin 10 is then located. This provides that the position of the ball itself will not be materially affected. Assuming the tee in place with the ball B located on loop 24, the person driving should take a position so that the ball will be supported on a line between his feet and the pin 10. In this way when club C strikes the ball, the ball in raising out of loop 24 will carry member 23 around to the position indicated in Figure 1 by the dotted line position, or often much beyond this. In this way member 23 is not actually struck by the club at all, is thus not subject to damage and in no way interferes with the follow-through of the club. 15 20 25 I have found it desirable, however, to make member 23 preferably of spring wire. In this way it will not be easily deformed, even though accidentally hit, as might occur when a player does not strike the ball fairly.
- 30 I have further provided a bend in member 23 at 28. It is intended that this will form a point of adjustment so that the user may bend mem-

ber 23 at the point 28 so as to provide the most desired height for the ball. Some players prefer to have the ball but slightly raised from the ground, while others, given to raising up slightly during their drive, may wish to have the ball held at considerable height. By providing a point as indicated the user will naturally make the adjustment at this point and will thus not interfere with the workings of the device.

The foregoing description and the accompanying drawing are believed to clearly disclose a preferred embodiment of my invention but it will be understood that this disclosure is merely illustrative and that such changes in the invention may be made as are fairly within the scope and spirit of the following claim:

What I claim is:

In a golf tee, the combination with a pin having an enlarged head, a washer on the pin spaced below the head, an annular shoulder rigid with the pin and located above the washer, and a retaining boss on the pin below the washer, of a vertically disposed coil rotatably mounted on the pin and confined between the head and shoulder, the upper end of the coil being in frictional engagement with the under side of the head, a horizontally disposed arm of resilient wire integral with the coil and extending in a plane above the coil, and a ball-supporting loop at the free end of the arm.
